Specification for Design.

Patented June 10, 1913.

Application filed March 12, 1913. Serial No. 753,849. Term of patent 3½ years.

To all whom it may concern:

Be it known that I, ALBERT GANCE, a citizen of the Republic of France, residing at 24 Rue de Provigny, Arcueil - Cachan, Seine, France, have invented a new, original, and ornamental Design for a Mount for Pince-Nez, of which the following is a specification, reference being had therein to the accompanying drawing.

The mount for pince-nez shown in elevation in Figure 1, and in side elevation in Fig. 2, comprises a bent spring blade a secured at each of its ends, by means of two small screws b, to a part c comprising two lateral projections d and e, the latter being in the shape of staple enabling it to engage with one of the glasses provided with a hole with which engages a screw f. One of the ends of the part c forms a small shackle or staple g with which engages one of the ends of a part h held on the same by means of a screw i, the part h being extended downward where it terminates in a small shackle j with which engages one of the glasses. In the interior of the said part is secured a packing k of suitable material which is striated and it is the two parts h which form the plate intended to grip the nose.

Claim.

The ornamental design for a mount for pince-nez as shown and described.

In testimony whereof I affix my signature in presence of two witnesses.

ALBERT GANCE.
